UNITED STATES PATENT OFFICE.

JOHN KAYLOR, OF DECATUR, ILLINOIS.

SEEDING DEVICE FOR CORN-PLANTERS.

SPECIFICATION forming part of Letters Patent No. 734,717, dated July 28, 1903.

Application filed December 3, 1902. Serial No. 133,698. (No model.)

To all whom it may concern:

Be it known that I, JOHN KAYLOR, a citizen of the United States, residing at Decatur, in the county of Macon and State of Illinois, have 5 invented certain new and useful Improvements in Seeding Devices for Corn-Planters, of which the following is a specification, reference being had to the accompanying drawings.

10 My invention relates to seeding devices for corn-planters, and particularly to improvements in means for insuring grains of corn being fed edgewise from the rotary seed-plate proper into cells or pockets arranged annularly around such seed-plate. It is a well-known fact that while grains of corn differ considerably from each other in their length or width they differ much less in their thickness—that is to say, in their narrowest diameter— 15 and my present invention is designed to take advantage of this fact, and is designed also to provide each cell or pocket into which the grains of corn are fed edgewise with a cover-plate having both a limited rising-and-falling movement and a limited amount of forward-and-backward movement, whereby grains of corn fed edgewise beneath such cover-plates will be properly seated in their cells or pockets, although varying considerably in either breadth or thickness, or both, 20 from the breadth and thickness of ordinary grains of corn. I attain this object by the means shown in the drawings and hereinafter specifically described. That which I regard as new will be set forth in the claims.

25 In the accompanying drawings, Figure 1 is a top or plan view. Fig. 2 is a vertical section taken at line 2-2 of Fig. 1. Fig. 3 is an enlarged view of the seed-plate with the cutting-off plate removed; and Fig. 4 is a detail, being an inner end view of one of the cell or pocket covers.

30 Referring to said figures of the drawings, 10 indicates an ordinary annular bottom plate 45 having the usual vertical flange 11, around which is adapted to be placed the lower end of an ordinary cylindrical seedbox 12.

13 indicates a downwardly-projecting bracket, preferably formed with the bottom-plate 10, from which rises a central conical hub portion 14, preferably cast integral with the bottom plate 10 and bracket 13.

15 indicates a ring surrounding the hub

portion 14 and resting on a shoulder or series of shoulders 16, formed on such hub portion, 55 said ring being provided with a beveled gear 17, adapted to mesh with another beveled gear 18, suitably secured on one end of a driving-shaft 19.

20 indicates an annular seed-plate, which, 60 as best shown in Fig. 2, is formed with its upper surface beveled downward from its center—that is to say, sloping downward toward its periphery—and through a central opening in which the upper end of the hub 65 portion 14 projects. This seed-plate 20 is suitably connected to the ring 15, so as to be driven therewith, and the connection between the plate 20 and said ring 15 should be of a character to enable the plate to be easily disconnected therefrom, and I have therefore shown a connection between these two parts of the ordinary kind—namely, complementary projections and notches. At the edge of the plate 20, and preferably formed therewith, is 70 a series of short vertical projections 21, located at regular intervals with their inner or forward faces substantially in line with the edge of the plate 20, such forward or inner faces being preferably rounded, so as to present no obstructive corners to the grains of corn that may be moved toward and past them. From the rear sides of these projections 21 extends an annular horizontal piece 22, the 75 upper face of which is below the tops of the 80 said projections 21 and somewhat higher than the surface of the plate 20 near the periphery of said plate.

23 indicates an annular vertical wall secured to or formed with the horizontal extension-piece 22, which wall is on the upper face 90 of said piece 22 and located near the outer edge thereof.

24 indicates a series of cover-plates each provided with a stem 25, that projects through 95 an opening 26 in the annular wall 23, said opening being slightly larger than the stem 25, whereby the forward or inner end of the cover-plate 24 will be allowed a limited amount of up-and-down movement.

27 indicates a cotter-pin passing through the stem 25 in rear of the wall 23, which effectually prevents accidental disengagement of the cover-plate from the wall.

28 indicates a coiled spring around the stem 105 25 of each cover-plate and bearing against

the inner face of said wall 23 and the rear of the cover-plate, the tendency of such spring being to keep the cover-plate projected toward the seed-plate 20. As shown, each of these 5 cover-plates lies between two adjacent vertical projections 21, but does not fit between such projections close enough to prevent the plate from having the free limited movements intended. Beneath each cover- 10 plate in the horizontally-projecting piece 22 is formed an opening 29, one of which is clearly shown near the lower end of Fig. 3, where one of the cover-plates is represented as broken off. Into each of these openings 29 15 projects a downward ledge 30, formed on the under side of each cover-plate 24, which forms in the construction shown the back and one side wall of the cell or pocket that receives the corn. The better to facilitate the entrance of a grain of corn into each opening 29 20 the surface of the plate 20 opposite each of said openings is preferably slightly beveled, as indicated in Fig. 2. As shown in the drawings, each plate 24 is provided with 25 small side wings 31, which rest upon the surface of the horizontally-extending piece 22.

32 indicates a cut-off plate consisting, as shown, of a ring portion fitting within the upturned vertical portion or flange 11 of the bottom plate 10, to which it is preferably removably attached in the ordinary way by means of interfitting projections and recesses, as will be well understood. The cut-off plate or ring 32 also has a hub portion 33, the ring portion 35 and the hub portion being connected together by suitable arms 34. The hub portion 33 rests upon a suitable shoulder formed on the upper portion of the other hub portion 14 and is locked in place by a thumb-nut that is 40 screwed down upon a bolt 35, the head of which is suitably held in the interior of the hub portion 14.

36 indicates an angular bracket carried by the cut-off plate 32, to the vertical portion of 45 which bracket are secured suitable guard-plates 37, the lower ends of which project down below the cut-off plate close to the surface of the seed-plate 20 and are intended to prevent grains of corn from passing out 50 through the large discharge-opening 38, that is formed in the bottom plate 10. 39 indicates a spring-plate also secured to the inner face of the vertical portion of said angular bracket, near one end thereof and near one 55 end of the large discharge-opening 38, referred to, and acting in the usual manner to prevent grains of corn from passing to such opening except when such grains of corn are within the seed cells or pockets described.

60 40 indicates a spring-arm, one end of which is attached to the vertical portion of the bracket 37, the other or free end lying close to the inner edge of the cut-off plate and also close to the upper surface of the seed-plate 65 20. Such arm is arranged and adapted to contact with any grains of corn that may be projecting from beneath any of the plates 24

and acts to settle a grain of corn properly in place under its plate 24, or in case two grains of corn should be partially wedged beneath 70 one plate 24 it acts to force one of such grains away, so as to permit the other one to properly settle in place beneath the plate.

41 indicates arms, which in the construction shown are secured to the under face of 75 the hub portion 33 and project over and in contact with the plate 20, or nearly so, so that as such plate is rotated the arms will act to direct the corn toward the edge of such plate. 80

It will be understood that through the gearing shown the plate 20 can be driven intermittently through the action of a check-row wire on the forks of a check-rower head or can be driven continuously by other means, the 85 first method of driving being, of course, when the machine is used for hill-planting and the second method when it is desired to use the machine as a drill-planter. In hill-planting it is highly desirable that the same number 90 of grains of corn be dropped in each hill, and with the grains of corn carried under the plates 24 it is evident that as the plates are spaced a uniform distance apart with each full operation of the check-rower forks the 95 seed-plate will be turned a certain distance and a certain number of grains necessarily dropped through the large opening 38 in the bottom plate 10.

By the construction shown it will be evident that grains of corn are adapted to be fed from the seed-plate 20 into the openings 29 below the cover-plates 24 and when in such position must rest on the bottom plate 10 with their side edges toward the side of the seedbox and will be swept along on such bottom plate as the seed-plate 20 rotates until they are brought over the discharge-opening 38. The spaces provided beneath the cover-plates 24 are of a size and shape that will not permit grains of corn to enter other than in an edgewise manner, and while the space between each cover-plate 24 and the seed-plate 20 is designed to admit a grain of corn in this manner without disturbing the normal position of a cover, yet in case a grain of corn of unusual thickness or unusually rounded is presented to such opening the cover will be raised or lifted a little at its forward end by the pressure of the grain at that point, being allowed this movement through the loose fit of its stem 25 in its hole 26 in the vertical wall 23, such hole 26 being, as before explained and as shown in Fig. 2, of larger diameter than the diameter of the stem. Again, if a grain of corn of greater width than ordinary passes edgewise beneath a cover-plate 24 such cover-plate is enabled to move back, so as to accommodate such grain of corn, overcoming in its backward movement the slight resistance offered by the light coiled spring wrapped around its stem, the backward movement being accomplished either through the pressure of the mass of corn in the seedbox 110 115 120 125 130

or through the effect of the pressure exerted on that particular grain of corn by the spring-arm 40. It will thus be seen that by my improved means I am enabled to provide cells or pockets which are adapted for receiving under all conditions only a single grain of corn and which under normal conditions will always receive a single grain of corn of ordinary size while the seed-plate is being rotated, 5 and yet if a grain of corn of unusual shape—that is, either unduly thick or wide—is presented to the opening of such cell or pocket it will by reason of the flexibility of the cover-plate be received and carried forward, so that 10 there is but very slight liability of the machine delivering through the opening 38 any number of grains except the predetermined number, which of course insures uniformity 15 in the amount deposited in each hill.

20 That which I claim as my invention, and desire to secure by Letters Patent, is—

1. The combination with a seed-plate, of a series of covers opposite the seed-plate and arranged over openings, each of which openings is adapted to receive a grain of corn, and means for flexibly securing such covers to permit them to have a backward-and-forward and a rising-and-falling movement, substantially as specified. 25

30 2. The combination with a seed-plate, of a series of covers opposite the seed-plate and arranged over openings, each of which openings is adapted to receive a grain of corn, and means for permitting a backward-and-forward movement of such covers, substantially as described. 35

3. The combination with a seed-plate, of a series of covers opposite the seed-plate and arranged over openings, each of which openings is adapted to receive a grain of corn, and means for holding said covers projected toward said plate, and means for permitting said covers to yield in a direction away from such seed-plate, substantially as specified. 40

45 4. The combination with a seed-plate, of a series of covers opposite the seed-plate and arranged over openings, each of which openings is adapted to receive a grain of corn, a support for said covers connected with said seed-plate, and means for permitting said covers to yield in a direction away from said seed-plate, substantially as specified. 50

55 5. The combination with a seed-plate, of a series of covers opposite the seed-plate and arranged over openings, each of which openings is adapted to receive a grain of corn, an extension beyond said seed-plate in which are formed said openings, and a vertical, annular wall carried by said extension, said wall 60 furnishing a support for said covers, substantially as specified.

65 6. The combination with a seed-plate, and an annular extension beyond the periphery of said plate, in which extension are openings adapted to receive grains of corn from the seed-plate, of a cover for each opening, each of said covers being provided with a stem, a

support carried by said annular extension and adapted to receive the said stems of the covers, and means for yieldingly holding said 70 covers toward said seed-plate, substantially as specified.

7. The combination with a seed-plate, and an annular extension beyond the periphery of said plate, in which extension are openings 75 adapted to receive grains of corn from the seed-plate, of a cover for each opening, each of said covers being provided with a stem, a support carried by said annular extension and adapted to receive the said stems of the 80 covers, and a coiled spring around the stem of each cover tending to normally hold said cover projected toward the said seed-plate, substantially as specified.

8. The combination with a seed-plate, and 85 an annular extension beyond the periphery of said plate, in which extension are openings adapted to receive grains of corn from the seed-plate, of a cover for each opening, each of said covers being provided with a 90 stem, and a support carried by said annular extension and provided with enlarged openings to receive said stems, whereby said covers are adapted to have a limited rising-and-falling movement, substantially as specified. 95

9. The combination with a seed-plate, and an annular extension beyond the periphery of said plate, in which extension are openings adapted to receive grains of corn from the seed-plate, of a cover for each opening, 100 each of said covers being provided with a stem, a support carried by said annular extension and provided with enlarged openings to receive said stems, and means for yieldingly holding said covers toward said seed-plate, whereby said covers are permitted a 105 limited rising-and-falling movement and a limited backward-and-forward movement, substantially as specified.

10. The combination with a seed-plate, and 110 an annular extension beyond the periphery of said plate, in which extension are openings adapted to receive grains of corn from said seed-plate, of a cover over each opening, each cover being provided with a ledge projecting into the opening over which the cover is placed and serving as a wall for such opening, substantially as specified.

11. The combination with a seed-plate, and 120 an annular extension beyond the periphery of said plate, in which extension are openings adapted to receive grains of corn from said seed-plate, of a cover over each opening, each cover being provided with a ledge projecting into the opening over which the cover 125 is placed and serving as a wall for such opening, and being also provided with side wings adapted to rest upon the upper surface of said annular extension at each side of the opening, substantially as specified.

JOHN KAYLOR.
